(57) **CLAIM**

The ornamental design for a spiral cutting tool, as shown and described.

DESCRIPTION

FIG. 1 is a perspective view of the claimed design;

FIG. 2 is a first side view thereof;

FIG. 3 is a second side view thereof;

FIG. 4 is a third side view thereof;

FIG. 5 is a fourth side view thereof;

FIG. 6 is a bottom view thereof; and,

FIG. 7 is a top view thereof.

The broken line disclosure shown superimposed on continuous claimed surfaces in the drawings are for illustrative purposes only and form no part of the claimed design.
